UNITED STATES PATENT OFFICE.

SAMUEL W. DOUGLASS, OF FORT COLLINS, COLORADO, ASSIGNOR TO THE
M. C. BULLOCK MANUFACTURING COMPANY, OF CHICAGO, ILLINOIS.

ROCK AND EARTH DRILLING MACHINE.

SPECIFICATION forming part of Letters Patent No. 443,750, dated December 30, 1890.

Application filed May 3, 1888. Serial No. 272,704. (No model.)

To all whom it may concern.

Be it known that I, SAMUEL W. DOUGLASS, of Fort Collins, in the county of Larimer and State of Colorado, have invented certain new and useful Improvements in Rock and Earth Drilling Machines; and I do hereby declare that the following is a full, clear, and exact description thereof, reference being had to the accompanying drawings, and to the letters ⁵ _{1c} of reference marked thereon, which form a part of this specification.

This invention relates to casing-sinking attachments or adjuncts for rotary rock and earth drills, and has for its object to provide ¹⁵ mechanism for running down a casing for a hole being bored by the same machine, and while the drill is at work or in the hole.

The nature of the invention will be understood from the following description of the ²⁰ accompanying drawings, and from the appended claims.

Figure 1 is a vertical section through the axis of the drill-spindle of a differentially-gearred screw-feed, as used in rotary rock and ²⁵ earth drills, said section being taken in a plane parallel with the face of the swivel-plate and showing the screw-threaded drill-spindle and two parallel screw-threaded auxiliary spindles for driving and feeding the ³⁰ casing, together with the casing-chuck and the connecting-gearing. Fig. 2 is a vertical section taken through the axis of the drill feeding and driving spindle at right angles to the face of the swivel-plate. Fig. 3 is a ³⁵ horizontal section taken in the line 3 3 of Figs. 1 and 2. Fig. 4 is a section in the same plane as Fig. 2 of the vertically-sliding casing-chuck and its guide. Fig. 5 is a horizontal section of the casing-chuck and its guide ⁴⁰ in the line 5 5 of Figs. 1 and 4.

A represents the hollow screw-threaded drill-driving spindle of a rotary rock or earth drill provided with a feather-way *a*.

A' is the drill-rod, held in the hollow spindle ⁴⁵ A in the usual or any approved manner.

B is a sleeve loosely embracing the spindle A, and provided with a beveled pinion B' at its lower end.

C is the beveled driving gear-wheel on the ⁵⁰ crank-shaft C' of the engine and meshing with the beveled pinion B' on the sleeve B.

D is a sliding clutch-sleeve embracing the spindle A and provided with a feather or spline *d*, which runs in the feather-way *a* of the spindle A. The upper end of the clutch-sleeve D is provided with projections *d' d'*, which interlock with similar projections *b'* on the lower end of the gear-sleeve B.

D' is a collar fitted to an annular groove *d²* in the clutch-sleeve, and connected with a lever D² for raising and lowering the clutch-sleeve.

E is the swivel-plate, which in the usual or any suitable manner is rotatably supported about the axis of the driving-shaft C', and ⁶⁵ carries the bearing-blocks F F' of the drill-spindle A and of the auxiliary spindles G G' for driving the casing-chuck, yet to be described. In the upper bearing-block F rotates the gear-sleeve B, being constructed to ⁷⁰ retain its engagement with the driving-gear C by annular flanges *c c*, as shown, while in the lower bearing-block F' rotates the thrust-nut O, which is interiorly threaded to fit the drill-spindle A, and constituting a feed-nut ⁷⁵ for said spindle. The thrust-nut O is retained in the bearing-block by suitable flanges or other form of shoulders, which in the present instance consist of the familiar roller thrust-bearing Q and the annular flange o. The ⁸⁰ thrust-nut O carries a loose pinion U and a fixed pinion R. The gear-sleeve B carries the two fixed pinions L and S.

The two auxiliary spindles G G' are placed one at each side of the drill-spindle A and preferably in the same plane therewith, and are provided with feather-ways, as shown in Fig. 3, in which fit feathers or splines on the prolonged sleeves G², which sleeves themselves rotate in the bearing-block F. Upon each of ⁸⁵ the sleeves G² is fitted a loose pinion M or M', which, however, may be made fast with the sleeve by means of any suitable clutch, the form of clutch here shown being the familiar cup friction-clutch, of which G³ is the movable part, being provided with the groove *g* for the usual collar (not shown) for throwing the clutch into and out of engagement. The pinions M M' engage with the pinion L on the sleeve B.

P P' are sleeve-nuts, which are interiorly threaded to fit the thread on the spindles G

G' and rotate in bearings in the lower bearing-block F'. On the lower prolonged ends of the sleeve-nuts P P' are fixed pinions T T', which mesh with the loose pinion U on the 5 sleeve-nut O. The nuts P P' are for the purpose of feeding the casing-spindles G G'.

The lower ends of the spindles G G' rotate in thrust-bearings I I' in the vertically-movable yoke or cross-head X, being provided 10 with flanges g g' or other provision for imparting end-thrust from the spindles to the yoke, by which the latter may be suspended and raised or lowered by vertical movement of said spindles. Above the bearings I I', as 15 here arranged, the spindles G G' are provided with fixed pinions H H'. Within the yoke X rotates the hollow casing-chuck J, which is supported by said yoke and has its axial opening j in line with the drill-spindle 20 A, and is provided with gear-teeth K, in position to mesh with the pinions H H', so that the chuck may receive its rotary motion from power imparted on opposite sides of it by said spindles. The casing-chuck J may be 25 contrived to hold a casing-tube J' by any suitable means, such means being here shown as consisting of set-screws j'.

Two counter-shafts are employed, one to rotate the feed-nut of the drill-spindle and 30 the other to rotate the feed-nuts of the casing-spindles. As here shown, these two counter-shafts W and V are arranged one within the other directly in front of the drill-spindle A, the shaft W being hollow and containing 35 the shaft V. The shaft W is supported in suitable bearings in the blocks F F', which project centrally for this purpose, as shown in Figs. 2 and 3. The shaft W is provided with suitable flanges w w, by which to retain 40 it vertically in place, and it carries the pinions M² and U' at its opposite ends in position to engage, respectively, with the pinions L and U on the gear-sleeve B and sleeve-nut O. The counter-shaft W is also divided be- 45 tween its bearings, and its proximate ends are provided with clutch members W', one of which is movable and splined to the sleeve, the devices for actuating the same being of the usual form and not herein shown. 50 In the concentric arrangement shown the interior counter-shaft V (here also shown as tubular) projects beyond the tubular shaft W at both ends, and at its projecting extremities carries pinions S' and R' at the 55 top and bottom, respectively. The former of these pinions is adapted to be engaged with or disengaged from the shaft V at pleasure by any suitable means, represented in this instance by a vertically-movable key V', fitted 60 to drop into the end of the tube V, and provided with a tang or feather v, which, reaching through a slot v' in the tube, engages in a notch or feather-way s in the inner periphery of the pinion. The pinion is shown provided 65 with an annular recess s' for half its depth, and the feather v is also made half or less than half the depth of the pinion, so that by

lifting the key V' only half the height of the pinion it may be made to clear the feather-way and release the pinion. This construction permits the presence of the retaining-nut V². The lower pinion R' on the counter-shaft V is fast on said shaft.

The pinions S and S' are made changeable, or, in other words, are adapted to be removed 75 and replaced with pinions of different relative sizes to vary the relative speeds of the gear-sleeve B and the counter-shaft V.

The operation of the machine thus equipped is as follows: Rotation of the shaft C' by the 80 engine rotates the gear-sleeve B, which, through the splined clutch D, rotates the drill-spindle A. Through the pinions S S' it also rotates the counter-shaft V. The counter-shaft V, through the pinions R' and R, 85 rotates the thrust-nut O, which feeds the drill-spindle A at a rate due to the relative numbers of teeth in the pinions S, S', R', R, and the pitch of the thread on the spindle. The sleeve-gear B also, through the pinions 90 L and M M', (when the latter are clutched,) rotates the splined sleeves G², which turn the spindles G and G', and these spindles, through the pinions H H', give a rotary motion to the casing-chuck J and the casing-tube J' secured therein. The spindles G G' are fed by differential rotation of the sleeve-nuts P P', which is accomplished through the pinion U' on the counter-shaft W, the idle-pinion U on the sleeve-nut O, and the pinions T 100 T' on the sleeve-nuts P P'.

By the mechanisms above pointed out, connected and operating as described, it is manifest that while the drill-rod A' is being run down to form the hole, either in rock or earth, 105 the casing-tube J' may be at the same time carried down into the hole as near to or as far from the drill-cutters as may be desired, and by change of the gears at a greater or less relative speed. If the clutch W' and the clutches 110 G³ G³ be in simultaneous engagement, as contemplated in ordinary use, the casing-chuck will be gradually fed down as it is being rotated. If the clutch W' be disengaged while the clutches G³ are retained in engagement, 115 then the casing-chuck will continue to rotate, but the feed-nuts P P' will be stationary and the casing-chuck will be raised. If the clutches G³ be disengaged and the clutch W' engaged, the casing will be thrust downward 120 without rotation. By means of the clutch-key V' the pinion S' may be freed from or engaged with the counter-shaft V, through which the feed-nut O is rotated, and, finally, by retracting the clutch D from engagement with the gear-sleeve B the drill-spindle may be 125 brought to rest while continuing the rotation or feed, or both, of the casing-chuck.

To raise the drill-spindle A, the feed-nut O will be held, for which purpose the key V' will be freed from the pinion S', and to raise the casing-spindles G G' the clutch W' will be disengaged and the feed-nuts P P' held. To hold these feed-nuts, non-rotating clutches

may be employed such as are now used in connection with the feed-nuts of drill-spindles, and these devices are therefore not shown.

5 By changing the combinations of gear-wheels in an obvious way the rapidity of the feed of both the drill-spindle and the casing-spindles may be varied at pleasure, or the casing-chuck can be simply rotated without 10 thrust either way.

It will be observed that the threads on the spindle A are shown left-handed and those on the spindles G G' are shown right-handed. This opposite arrangement of the spindle-15 threads is to enable the drill and the casing-chuck to be raised without reversing the engine, the downfeed being attained by a higher rotary speed of the feed-nuts than that of the spindles. For the general purposes of my 20 invention I do not wish to be limited to this opposite direction of the threads on the spindles; but such construction is specially claimed as a distinct improvement.

The guide Y may be attached to the swivel-25 plate or otherwise supported in line with the drill-spindle.

The use of a rotating screw-threaded drill-spindle, a rotating feed-nut thereon, and gear for giving the spindle and feed-nut differentiated motions are not broadly claimed herein.

I do not claim as my invention the construction herein shown, consisting of a drill-rod, a casing, gearing which rotates the drill-rod in one direction, and gearing which rotates the casing in the opposite direction, this 35 invention, broadly considered, being the invention of another.

I claim as my invention—

1. The combination, with a frame or swivel-40 plate, a drill-spindle, and driving and feed mechanism for actuating the drill-spindle, of a rotary casing-chuck, a movable support for the casing-chuck, one or more rotating screw-threaded spindles for operating the casing-chuck and its support, a feed-nut for advancing the spindles and moving the casing-chuck support, and connecting-gearing between the feed-nut and driving mechanism.

2. The combination, with a frame or swivel-45 plate, a drill-spindle, and driving and feed mechanism for actuating the drill-spindle, of a rotary casing-chuck, a movable support for the casing-chuck, one or more screw-threaded spindles for operating the casing-chuck and its support, a feed-nut applied to each casing-spindle, and clutch-gearing for operating the casing-spindles and their feed-nuts.

3. The combination, with a frame or swivel-50 plate, a drill-spindle, and driving and feed mechanism for the drill-spindle, of a rotary casing-chuck, a movable support for the casing-chuck, two rotary screw-threaded spindles G G', arranged at opposite sides of the

drill-spindle, said spindles G G' having thrust-bearings in the support for the casing-chuck 65 and being provided with pinions which gear with the casing-chuck, stationary rotatable feed-nuts embracing the spindles G G' and provided with pinions, clutch-pinions upon the spindles G G', and gearing intermediate 70 of the driving mechanism of the drill-spindle on the one hand and the casing-spindles and their feed-nuts on the other hand.

4. The combination, with the drill-spindle A, the driving or gear sleeve B, and the feed-75 nut O, of the casing-spindles G G', the tubular counter-shaft W, the counter-shaft V within the shaft W, and the gear-wheels for communicating motion from the gear-sleeve B to the casing-spindles and the several feed-nuts.

5. The combination, with a swivel plate or other support, of a drill-spindle A, gear-sleeve B, provided with pinions L and S, feed-nut O, provided with the fast pinion R and loose 85 pinion U, casing-spindles G G', each provided with a feather-way and with pinions H H', splined sleeves G², provided with clutch-pinions M M', feed-nuts P P', provided with pinions T T', counter-shaft W, provided with 90 pinions M² and U', and with a clutch intermediate of said pinions, counter-shaft V, provided with pinions S' and R' and intermediate clutch mechanism, movable casing-chuck support X, engaged with the spindles G G', 95 and rotating casing-chuck J, provided with gear engaging with the pinions H H', substantially as described.

6. The combination, with a movable casing-chuck support, a rotating casing-chuck 100 mounted in said support, and a spindle or spindles for rotating the chuck, of a guide for the support adapted to hold the latter from rotation while guiding it in line with the drill-spindle.

7. The combination, with a rotating screw-threaded drill-spindle and a rotary feed-nut for advancing and retracting the drill-spindle, of rotating screw-threaded casing-spindles which rotate in a direction opposite to 110 that of the drill-spindle, and which have their threads directed oppositely to those of the drill-spindle, rotatable feed-nuts on the casing-spindles, a driving mechanism, and intermediate gearing which gives motion simultaneously to both the feed-nuts of the drill-spindle and the feed-nuts of the casing-spindles.

In testimony that I claim the foregoing as my invention I affix my signature in presence 120 of two witnesses.

SAMUEL W. DOUGLASS.
